Wallace Durand,

By Frank C. Atty's.

UNITED STATES PATENT OFFICE.

WALLACE DURAND, OF NEWARK, NEW JERSEY.

DESIGN FOR A WATCHCASE.

SPECIFICATION forming part of Design No. 23,236, dated May 1, 1894.

Application filed February 28, 1894. Serial No. 501,875. Term of patent 7 years.

To all whom it may concern:

Be it known that I, WALLACE DURAND, a citizen of the United States, residing at Newark, in the county of Essex and State of New Jersey, have invented and produced a new and original Design for Watchcases; and I do hereby declare the following to be a full, clear, and exact description of the invention, such as will enable others skilled in the art to which it applies to make and use the same, reference being had to the accompanying drawings, and to letters of reference marked thereon, which form a part of this specification.

Figure 1 is a plan of the newly designed watch case. Fig. 2 is an edge view of the same.

The leading feature of the design consists in a watch case which is convex on the outer face and, at the central part of the convex side, ornamented with the figure of a man sitting astride of a figure of a mythical animal

and bearing in his hand a saucer or cup-shaped receptacle.

In said drawings, *a* indicates the watch, *b* the side face thereof which is convex at the edges as indicated in Fig. 2, and at the center part comparatively flat. The flattened center part is ornamented with a figure of a man, *c*, sitting astride of a figure, *d*, of a mythical animal, and bearing in his hand a saucer or cup-shaped receptacle, as though carrying water.

What I claim as new is—

The design for a watch case, herein shown and described.

In testimony that I claim the foregoing I have hereunto set my hand this 27th day of January, 1894.

WALLACE DURAND.
